DESIGN FOR AN INVERTIBLE STATUETTE

Lou Obstfeld, Brooklyn, N. Y., assignor of one-half to Abraham I. Obstfeld, New York, N. Y.

Application December 30, 1941, Serial No. 104,905

Term of patent 7 years

To all whom it may concern:

Be it known that I, Lou Obstfeld, a citizen of the United States and a resident of Brooklyn, in the county of Kings and State of New York, have invented a new, original, and ornamental Design for an Invertible Statuette, of which the following is a specification, reference being had to the accompanying drawing, forming a part thereof, wherein:

Fig. 1 is a front elevational view of an invertible statuette embodying my new design;

Fig. 2 is a side elevational view thereof; and

Fig. 3 is a front elevational view showing the statuette in inverted position.

I claim:

The ornamental design for an invertible statuette, substantially as shown.

LOU OBSTFELD.
